US00D956761S

(12) **United States Design Patent** (10) Patent No.: **US D956,761 S**
(45) Date of Patent: **** Jul. 5, 2022**

(54) **SMART CARD**

(71) Applicant: **Zwipe AS**, Oslo (NO)

(72) Inventor: **Kristian Trengereid**, Oslo (NO)

(73) Assignee: **ZWIPE AS**, Oslo (NO)

(**) Term: **15 Years**

(21) Appl. No.: **35/510,864**

(22) Filed: **Oct. 20, 2020**

(80) **Hague Agreement Data**

Int. Filing Date: **Oct. 20, 2020**

Int. Reg. No.: **DM/211424**

Int. Reg. Date: **Oct. 20, 2020**

Int. Reg. Pub. Date: **Dec. 4, 2020**

(30) **Foreign Application Priority Data**

Apr. 20, 2020 (EM) 007823232

(51) LOC (13) Cl. **14-02**

(52) U.S. Cl.

USPC **D14/436**; D19/

(58) **Field of Classification Search**

USPC D14/385, 436, 437; D19/9, 10, 11, 12

CPC G06Q 20/341; G06Q 20/40145; G06Q 20/352; G06Q 20/4014

See application file for complete search history.

(74) Attorney, Agent, or Firm — Eversheds Sutherland (US) LLP

(57) **CLAIM**

The ornamental design for a smart card, as shown and described.

DESCRIPTION

6., 10. Smart card

6.1 : Perspective

6.2 : Front

6.3 : Back

6.4 : Left

6.5 : Right

6.6 : Top

6.7 : Bottom

10.1 : Perspective

10.2 : Front

10.3 : Back

10.4 : Left

10.5 : Right

10.6 : Top

10.7 : Bottom

The broken lines in reproductions 10.1-10.3 depict environmental structure that forms no part of the claimed design.

1 Claim, 14 Drawing Sheets
